UNITED STATES PATENT OFFICE.

THOMAS LOUIS SHERMAN, OF CAULFIELD, VICTORIA, AUSTRALIA, ASSIGNOR TO
CRANKLESS ENGINES LIMITED, OF MELBOURNE, AUSTRALIA.

SLIPPER GUIDE FOR CRANKLESS ENGINES.

Application filed April 27, 1925, Serial No. 26,316, and in Australia July 8, 1924.

The object of the present invention is an improved means for guiding, or restraining the motion, of the slippers which form the bearing elements between the pistons and slants or swash-plates of crankless engines such as are described in the United States Patent No. 1,409,057 dated March 7, 1922.

Practical applications of the present invention are shown in the accompanying drawings, in which Fig. 1 is a longitudinal section of a piston, including the improved device; Figs. 2 and 3 are cross sections respectively on the lines II, II and III, III of Fig. 1; Fig. 4 is a cross-section similar to Fig. 3, but showing a modification of the improvement, consisting of a variation of the form of the guiding means, of which a detail is shown in Fig. 5. Fig. 6, shows another form of the guide-piece, alternative 20 to the form shown in Figs. 1 and 3, and Fig. 7 shows still another form of the guide-piece.

As shown in the drawings, particularly Fig. 1, the double-ended piston 5, 5, coacts with the slant 1, of which a portion only is shown, (Fig. 1), through the slippers 11, 11 which having spherical bosses 13, 14 are universally pivoted on the piston cups 15, 16. The above-mentioned parts are all similar to those described in said patent 30 and indicated by corresponding numbers in the drawings, particularly Figs. 4, 5 and 7, attached thereto. As shown in those figures the slippers 11, 11 are prevented from revolving around the axes of the piston 5, 5, by being each furnished with an extension formed with a ball 55, engaging in a slot 53 formed in the bar or yoke-piece 8 of the piston 5, 5. According to the present invention the extension 2 of the slipper 11, is 40 made of cylindrical shape, the construction in this particular being the same as that described in the application Serial No. 629,501 filed in the United States Patent Office, April 2, 1923. According to the latter, the slot in which the slipper-extension engages is formed in the yoke-piece of the piston. It has however been found in practice that there is a difficulty in securing correct mutual alignment of the slipper-extension and 50 slot so as to ensure that the cylindrical extension shall bear on the side of the slot along its whole length, thus securing the desired line-contact. In default of such alignment, point contact only, at one edge 55 of the slot, is obtained. Similarly in the

use of a ball-shaped extension, as in said United States Patent 1,409,057, point contact only is provided. It is the purpose of the present invention to diminish the rate of wear of the parts, by securing line or surface contact by the use of special guide-pieces now to be described. In the form of construction shown in Figs. 1, 2 and 3, the guide-pieces 3, 3, carried by the yoke-portion 8 of the piston 5, 5, are formed with a slot 4, of rectangular section (Fig. 2) such slot receiving the corresponding cylindrical slipper extension 2. The slots 4 may extend completely through the thickness of the guide-pieces 3, or as shown in Figs. 1 and 2, 60 in order to give additional strength at their sides, the depth of the slots may be less than the thickness of the guide-pieces. In either case it is necessary for satisfactory operation that the slots 4 shall be sufficiently deep and 70 the extensions 2 sufficiently long for the latter to reach as far as, and at least a small distance beyond, the axis of the guide-piece 3. The guide-pieces 3, 3, are housed in a longitudinal recess 6, formed in the yoke 8, 75 and are retained in position endwise by cap-pieces 7, 7, secured to the inside of the piston as by screws 9, 9. The guide-pieces 3, 3, are mounted so as to be free to rotate to at least some small extent about their longitudinal 80 axes, as by being turned to cylindrical form on their external surface, fitting the recess 6, correspondingly bored to receive them. The outer ends of the guide-pieces 3, may extend as shown at 4^a, through the cap-pieces 7, 7, and these ends may thus provide 85 additional bearings or the sole bearings for the rotary movement of the guide-pieces. In order to prevent slackness of the guide-pieces 3, 3, in a longitudinal direction they 90 may be fitted with a common helical spring 10, inserted in axial holes in the ends of the guide-pieces as shown in Fig. 1.

In the forms of construction of the device shown in Figs. 1 and 2, and in Fig. 6 to be referred to again hereinafter, the slipper extension 2 fits the slot 4 in the guide-piece 3, and in operation bears directly on one or other side of the slot. In the alternative construction shown in Figs. 4 and 5, the extension 2 is fitted with a block 12, bored to fit it, and having flat sides 12^a, 12^b, upon which it fits the slot 4. In the operation of this form of the device the extension 2 has 105 a small rotational motion in the block 12, 110

2
while the latter has a purely sliding motion longitudinally in the slot 4, the bearing contacts of both types of motion being effected over surfaces, instead of on a line as in the construction previously described. In the form shown in Figs. 4 and 5 the slots preferably extend completely through the thickness of the guide-pieces as shown. In order to accommodate the block 12, the guide-pieces in the alternative construction are made of greater width than in the construction according to Figs. 1 and 2, and they may conveniently be made of cylindrical shape with flat sides as shown in Fig. 4. 15 The same construction may be adopted, for the sake of additional strength, even when no blocks are used, this variation being indicated in Fig. 6.

It will be understood that the guide-pieces 20 3, 3, are made as two separate pieces in order to allow of their aligning themselves independently to small variations of the slipper-extensions 2, 2. In some cases however, the piston pressure being exerted upon one 25 side only of the slippers 11, 11 and at a time, it is permissible to combine the guide-pieces 3, 3, into one, as indicated by 23, in Fig. 7. The extension piece 2, of the slipper which carries the piston load at any instant, then 30 controls the rotation of the guide-pieces 23, by line-contact on one or other side of the slot, 24, and the extension piece of the other slipper is aligned by similar contact, slightly displacing the other slipper, which being 35 free from load is able to take up the required position. In this modification a single extended slot 24, may be used, receiving both slipper extensions 2, 2, in lieu of separate slots 4 as shown in Figs. 1, 5 and 6.

40 It is to be understood that the application of the invention is not limited to double-ended pistons as above described as it is equally applicable to a single-ended piston having an extension (equivalent to the yoke-portion 8) to the opposite side of the slant from the piston which extension carries a 45 second slipper. Such a construction is illustrated in Fig. 8, of said United States Patent No. 1,409,057, to which reference has 50 been previously made herein.

I claim:—

55 1. In crankless engines of the type set forth, a slant, a piston element, a slipper articulated to said element and making lubricated working contact with the slant, a yoke extension on said piston element, a slipper guide element rotatable in said member about an axis parallel to the longitudinal axis of the piston, a longitudinal slot in said member, and an extension on 60 said slipper slidably engaging said slot.

65 2. In crankless engines of the type set forth, a slant, a piston element, a yoke extension on said element, a pair of guide members rotatable about a common longi-

tudinal axis in said extension parallel to the longitudinal axis of the piston element, a longitudinal slot in each of said members, a pair of slippers articulated to said piston element one on either side of the slant and 70 in lubricated working contact therewith, and a projection of each of said slippers slidably engaging with one of said slots.

3. In crankless engines of the type specified, a slant, a piston element, a slipper articulated to said element and making lubricated working contact with the slant, a yoke extension on said element, a projection on said slipper, a block mounted and rotatable upon said projection, a guide member in said yoke extension rotatable about an axis parallel to the piston element, and a longitudinal slot in said guide member in slidable engagement with said block. 75

4. In crankless engines of the type specified, a slant, a piston element, a yoke extension on said element, a pair of slippers articulated to said element and located one on each side and in lubricated working contact with the slant, a pair of guide members 80 rotatable about a common longitudinal axis in said yoke extension parallel to the longitudinal axis of the piston element, a longitudinal slot in each of said guide members, a projection on each of said guide members, 85 and a block on each projection, each of said blocks in slidable engagement with one of said slots. 90

5. In crankless engines, a slant, a piston element, a slipper articulated to said element and making lubricated working contact with the slant, a yoke extension on said piston element, a slipper guide block rotatable in said yoke member about an axis parallel to the longitudinal axis of the piston, said 100 block formed with a pair of oppositely disposed flat sides and a pair of oppositely disposed cylindrical sides, a longitudinal slot in said block, a projection on said slipper, a block mounted on and rotatable 105 relative to the projection, said block slidably engaging with said slot. 110

6. In crankless engines, a slant, a piston element, a yoke extension on said element, a pair of guide blocks rotatable about a common longitudinal axis in said yoke extension, said axis parallel to the longitudinal axis of the piston element, a pair of slippers articulated to said piston element and located one on each side and in lubricated 115 working contact with the slant, a longitudinal slot in each of said guide blocks, a pair of oppositely disposed flat sides and a pair of oppositely disposed cylindrical sides 120 on each of said guide blocks, a projection on each slipper and a block on each projection 125 slidably engaging with one of said slots.

Dated this 26th day of March 1925.

T. L. SHERMAN.
